UNITED STATES PATENT OFFICE.

WILLIAM F. BRENNAN, OF COLLINSVILLE, ILLINOIS.

EFFICIENCY-TABLE.

1,394,405.

Specification of Letters Patent.

Patented Oct. 18, 1921.

Application filed January 17, 1921. Serial No. 437,946.

To all whom it may concern:

Be it known that I, WILLIAM F. BRENNAN, a citizen of the United States, residing at Collinsville, Madison county, Illinois, 5 have invented new and useful Improvements in Efficiency-Tables, of which the following is a specification.

This invention relates to efficiency tables which are adaptable to various uses.

10 An object of the invention is to provide a table having an infant's chair pivotally supported thereby and capable of movement to a position at one side of the table, and to a position under the table, and provided 15 with means for supporting the chair in a selected adjusted position at the side of the table.

Another object of the invention is to provide an extension table with a removable 20 top leaf at the end and a receptacle in the space below the removable top leaf adapted to be used for different purposes, and a guard adapted to be applied to the side edge of the table top above the receptacle.

25 Another object of the invention is to provide an extension table with a removable top leaf and novel means for retaining the same in position on the table.

In the drawings, in which I have shown 30 a preferred embodiment of the invention,

Figure 1 is a side elevation of my improved table in its extended arrangement.

Fig. 2 is a plan view of the table with the extension leaves removed showing the receptacle at one end of the table.

Fig. 3 is a side elevation of the table in the form shown in Fig. 2.

Fig. 4 is an end elevation of the table with the receptacle at the end thereof removed, 40 and the infant's chair in its lower position below the table.

Fig. 5 is a similar view with the infant's chair supported at the side of the table.

Fig. 6 is a view showing the improved 45 means for holding one of the removable extension leaves on the table.

Fig. 7 is a view showing the device for holding the infant's chair in different adjusted positions.

50 As shown my improved table is of the extension type and comprises a frame 1 at one end of the table and a frame 2 at the opposite end of the table, held in proper relative positions which permit extension adjustments thereof by the usual extension guides 3. The extension guides 3 may be of any

usual or known construction, generally used in extension tables. The specific construction and arrangement of the guides 3 are immaterial to an understanding of the present invention and, for that reason, are not shown or described in detail. The frame 1 is supported by legs 4 and the frame 2 is supported by legs 5 while the central or extension portion of the table is supported by 60 a leg 6. All of the table legs may be provided with caster rollers 7 if desired.

Upon the frame 1 a top leaf 8 is permanently secured. A top leaf 9 is provided for the frame 2. The leaf 9 is removable 70 and is formed with recesses arranged to receive the arms or lugs 10 (Fig. 6) extending upwardly from the frame 2 so that the top leaf 9 will be held in proper alignment with the remaining parts of the table. I also provide removable keys 11 arranged to be inserted in holes formed in the top leaf 9 and to pass through holes in the arms or projections 10 to lock the leaf 9 in connection with the table. Preferably the outer ends of 80 the keys 11 are formed with manually engageable parts 12 whereby said keys may be easily inserted and withdrawn.

If desired, the table may be extended only to the length shown in Fig. 2 in which 85 the adjacent side edges of the top leaves 8 and 9 will contact; or, if desired, the table may be further extended and made continuous by a number of removable extension leaves 13 placed upon the extension frame 3. 90 between the leaves 8 and 9 and held in connection therewith by the usual dowel pin arrangement (not shown).

The infant's chair 14 is pivoted to a support 15 so that the infant's chair may be 95 turned laterally on said support. The support 15 is pivoted horizontally in a supporting bracket comprising an arm 16 having its upper end pivoted to one of the table legs 4 at 17, and having a short inner 100 arm 18. The support 15 is pivoted for turning movements between the arms 16 and 18 so that the parts may be moved to the positions shown in Fig. 4, or to the positions shown in Fig. 5 as desired. When in the 105 positions shown in Fig. 4 the chair is under the table out of the way and may be retained in a desired adjustment by means of a key 19 arranged to pass through a hole in the arm 18 and engage the support 15 to prevent the support 15 from turning on its 110 pivots. When the chair is raised to a posi-

tion at the side of the table (Fig. 5) the key 19 is withdrawn to permit the chair to be turned to the position shown, after which said key is placed in position to prevent 5 the support 15 from turning on its pivots. An element 20 is pivoted to the adjacent table leg 4 for engagement with the arm 16 of the bracket to support the chair at the side of the table. When it is desired to 10 lower the chair under the table the element 20 is disengaged from the bracket, permitting the chair to move downwardly to a position under the table as shown.

The receptacle which is included in the 15 invention and which is capable of movement between the legs 5 of the table to a position under the removable leaf 9 may be in the form shown. As shown, the receptacle is in the form of a crib 21 supported on caster 20 rollers 22 and is of a width approximately equal to the width of the removable leaf 9, although the dimensions of the receptacle may be varied. When it is desired to use the 25 table for any purpose and at the same time to use the receptacle 21 the extension leaves 9 and 13 may be removed from the table and the length of the table may be reduced as shown in Fig. 2, in which the receptacle 21 is conveniently located at the side of the fixed 30 table leaf 8. To prevent articles from being pushed off of the table into the receptacle 21, and for other useful purposes, I provide a guard 23. The guard 23 may be placed at the side edge of the fixed table leaf 8 and is 35 equipped with projections 24 arranged to engage in appropriate recesses in the table frame so that the guard will be securely held in position.

A table embodying the improvements de- 40 scribed is a genuine household convenience. An infant's chair arranged and supported in connection with the table may be conveniently placed in position for use, or out of the way under the table when not in use as 45 desired. Furthermore, the infant may be kept in the chair at the side of the table and the table may be used for household purposes at the same time.

The crib or receptacle 21 arranged for use 50 in association with the table may be applied

to various uses, whether as a crib for an infant or as a receptacle for articles being placed on or removed from the table, or other uses. The guard 23 will prevent articles from being pushed off the table into the 55 receptacle and will also serve as a guard to prevent a child in the crib from pulling articles from the table when the receptacle is used as an infant's crib.

The table is constructed so as to be adapted 60 for use in connection with the improvements described. It is apparent that all of the intended purposes are obtained in a highly satisfactory manner. The specific construction and arrangement of the parts may be varied 65 within equivalent limits without departure from the invention.

What I claim and desire to secure by Letters Patent, is:—

1. A table for household use, comprising 70 supporting legs, a bracket including two arms and having one end of one of said arms pivoted to one of said legs and being movable to and from an outwardly extended position, an element for supporting said bracket in an 75 outwardly extended position, a horizontal support mounted between said arms for horizontal turning movements to support a chair upright in any position of the bracket, a chair pivoted on said support for horizontal 80 turning movement relative to said support in any position of the bracket, and a device for holding said support from turning relative to said bracket.

2. A table for household use, comprising 85 supporting legs, an arm having one end pivoted to one of said legs and being movable from a vertical position to a position in 90 which said arm extends outwardly from the leg to which it is pivoted, a short arm in connection with the first-named arm, a support having its end pivoted to said arms and arranged for horizontal turning movement, a chair pivoted with said support for horizontal 95 turning movement, a device for locking said support from turning, and an element supported by the table for holding the first-named arm in its outwardly extended position.

WILLIAM F. BRENNAN.
